UNITED STATES PATENT OFFICE.

WILLIAM HENRY MORGAN AND CLARENCE L. TAYLOR, OF ALLIANCE, OHIO;
SAID TAYLOR ASSIGNOR TO THE MORGAN ENGINEERING COMPANY, OF
SAME PLACE.

CRANE.

SPECIFICATION forming part of Letters Patent No. 655,367, dated August 7, 1900.

Application filed July 1, 1899. Serial No. 722,592. (No model.)

To all whom it may concern:

Be it known that we, WILLIAM HENRY MORGAN and CLARENCE L. TAYLOR, of Alliance, in the county of Stark and State of Ohio, have invented certain new and useful Improvements in Cranes; and we do hereby declare the following to be a full, clear, and exact description of the invention, such as will enable others skilled in the art to which it applies to make and use the same.

Our invention relates to an improvement in cranes adapted particularly for forge-shops, the object being to provide an overhead traveling crane with means for manipulating the forging—such as elevating or lowering it, turning it horizontally, and rotating it; and our improvement consists in the parts and combinations of parts, as will be more fully described, and pointed out in the claims.

In the accompanying drawings, Figure 1 is a view in elevation of a crane embodying our invention. Fig. 2 is a plan view of the trolley; Fig. 3, a side view of same. Fig. 4 is a view of the mechanism for rotating the forging, and Fig. 5 is a diagrammatic view of the elevating and lowering mechanism.

A represents an overhead traveling bridge propelled by the motor B. This motor actuates the shaft C, running lengthwise one of the bridge-girders, and the shaft is provided at its ends with the pinions a, engaging the larger pinions b, fast to the flanged track-wheels e, which latter rest and move on the elevated rails.

Mounted and moving on the upper faces of the bridge-girders is the trolley D. This trolley is carried by the flanged wheels d' and is propelled longitudinally on rails on the bridge by a motor and gearing in the ordinary manner and is provided on its upper face with a circular trackway e', on which the upper section D' of the trolley rests and moves. This upper section D' of the trolley is provided with a depending circular flange or rail e², which latter rests over the circular trackway e' and on the conical rollers e³, the trunnions e⁴ of the entire series of which are journaled in the circular rings e⁵, one of which connects the outer ends of the rollers, while another (not shown) connects their inner

ends. With this construction it will be seen that the top section D' of the trolley can be rotated or turned on the lower section. Hence any work suspended from the upper section can be turned horizontally, so as to bring the work under the hammer or other tool irrespective of the location of the latter with respect to the furnace.

Secured on the upper section D' of the trolley is the motor E, the armature-shaft of which is provided with a bevel-gear f, which meshes with a bevel-gear f' on the upper end of vertical shaft f². This shaft is mounted on the upper section D' of the trolley and is provided at its lower end with a pinion f³, which engages the circular rack f⁴ on the lower section D of the trolley. By means of this motor and gearing the upper section D' of the trolley can be turned on the lower section, and thus turn the work horizontally, as previously described.

Secured on the upper face of the movable section D' of the trolley are the two motors G and G', the former of which we term the "revolving" motor and the latter the "hoisting" motor. These motors are geared up to a system of gearing for actuating pocketed sheaves or drums supporting the cables carrying the ingot or work to be forged, so that said ingot can be raised or lowered and revolved, the several movements of raising or lowering and revolving being simultaneous or independent, as desired. The hoisting-motor G' carries on its armature-shaft the small pinion g, which meshes with a larger toothed wheel g' on shaft g². This shaft is journaled in bearings in the motor-easing and also in bearing g¹ and carries at its other end the small pinion g¹, meshing with the large toothed wheel H. This wheel H is loosely mounted on shaft H' and is provided with a hub h and an integral pinion h'.

Mounted on the hub h is the internal and external spur-wheel H², the external teeth of which mesh with the pinion h² on the revolving motor-shaft, while the internal teeth mesh with the series of pinions h³, loosely mounted on the bearings h⁴, carried by the disk h⁵, keyed to shaft H', the pinions h³ also meshing with the wheel h', fast to toothed

wheel H. This shaft also carries the pocketed sheaves h⁷, which latter are keyed to the shaft so as to turn therewith.

Toothed wheel H which, as before stated, 5 is loose on its shaft, meshes with the toothed wheel H³, which is loose on the shaft H⁴ and is identical in structure with wheel H and has a hub h⁸ and a small toothed wheel h⁹. Mounted on the hub h⁸ is the internal and 10 external spur-wheel H⁵, the outer teeth of which mesh with the pinion h² on the revolving motor-shaft, while the internal teeth thereof engage the pinions h¹⁰ on the bearings h¹¹, carried by the disk h¹², rigidly keyed 15 to shaft H⁴. The pinions h¹⁰ also mesh with the pinion h⁹, which is integral with the toothed wheel H³. Secured to shaft H⁴ are the pocketed sheaves h¹⁴.

Two endless chains are passed over the 20 sheaves h⁷ and h¹⁴, each chain passing up over one sheave h⁷ and also over the oppositely-disposed sheave h¹⁴ and falling in a loop below the sheaves. The two chains I thus supported each carries in its lower looped 25 end a pocketed sheave J, the two sheaves J being mounted on opposite sides of the cross-head K.

Secured to the wheels J, so as to rotate therewith, are the pinions L, and suspended 30 from the cross-head K is the yoke L', the upper head of which is supported by a spring L², resting on the cross-head, while the lower bifurcated end carries the sprocket-wheel L³ and the pinions L⁴, the latter being connected 35 to the sprocket-wheel so as to turn therewith. The pinions L⁴ are geared up to the pinions L by the pinions L⁵, which, as clearly shown in Fig. 1, are carried on the jointed arms M, which latter are loosely mounted at 40 their ends on the bearings for the pinions L and L⁴. By this construction the wheels L⁵ follow up the wheels L⁴ under varying tensions of spring L² and are always in engagement therewith, so as to impart rotary motion 45 thereto from the wheels L.

An endless chain N is carried by the sprocket-wheel L³ and forms a loop in which the ingot or forging or tool for manipulating the forging rests.

50 For the purpose of illustrating the operation of the parts which elevate, lower, and revolve the forging we have used a series of arrows marked 1 for indicating the movements of the several parts while raising or lowering the forging and arrows marked 2 for indicating the movements while revolving the forging, the several arrows being represented above the shafts.

For lowering the load the hoist-motor G' 60 would be operated to turn wheel H in the direction indicated by the arrow thereon and it in turn, meshing with toothed wheel H³, will drive it, as indicated. The wheel H would transmit motion through its pinion h' to the pinions h⁸ and from the latter through the disk h⁵ to shaft H' and its pocketed sheaves h¹⁴, rotating the latter in the direction of an

arrow 1. The rotation of wheel H³ imparts rotation through pinion h⁹ to pinions h¹⁰ and from the latter through disk h¹² and shaft H⁴ to the pocketed sheaves h¹⁴. By reversing the direction of the rotation of the motor G a reverse motion will be imparted to the sheaves h⁷ and h¹⁴, thus lifting the load carried by the chain-blocks. The links of the 75 chain I rest in the pockets of the sheaves, with the slack of the chain hanging below the sheaves, and as the load is lowered this slack is taken up and as it is elevated the slack is increased.

While hoisting or lowering alone the revolving motor G is at rest and the pinion h⁹, engaging the wheels H² and H⁵, holds them against movement. By now stopping the hoisting motor and starting the revolving motor 80 motion is imparted through pinion h² to the wheels H² and H⁵, which, as before explained, are loose on the hubs of the wheels H and H³. The wheels H² and H⁵ are revolved in the same direction as indicated by the arrows 85 2, and they in turn carry the pinions h⁸ and h¹⁰ around on their respective pinions h' and h⁹, thus rotating the disks h⁵ and h¹² and imparting through said disks motion to the shafts H' and H⁴ and to the pocketed sheaves 90 h⁷ and h¹⁴, the latter revolving in the same direction. With the sheaves revolving in the same direction it will be seen that the chains I instead of elevating or lowering the sheaves J, carrying the chain-block, simply revolve 95 these wheels, and the latter, through the intervention of the pinions L, L⁵, and L⁴, revolve sprocket-wheel L³ and the endless chain N, carried thereby, and as the forging or tool is carried by the chain N it will be revolved in 100 the direction of movement of the chain.

By imparting motion to the hoisting and revolving motors at the same time and at different rates of speed it will be seen that the forging can be elevated or lowered and revolved simultaneously and by revolving the upper section D' of the trolley the forging can be turned. Any one of these movements can be imparted singly or they can be imparted simultaneously, excepting, of course, hoisting 105 and lowering. Hence it will be seen that the forging can be carried to any part of the mill and manipulated to bring any part of same in a position to be operated upon.

It is evident that many slight changes might 110 be made in the relative arrangement of parts herein shown and described without departing from the spirit and scope of our invention. Hence we would have it understood that we do not wish to confine ourselves to the exact 115 construction herein shown and described; but,

Having fully described our invention, what we claim as new, and desire to secure by Letters Patent, is—

1. In an overhead traveling crane, the combination with a traveling bridge and a trolley thereon, the upper section of the latter constructed to rotate, of an endless chain carried

by said upper section of the trolley and passing downwardly between the bridge-girders and means for hoisting and lowering and for revolving said chain.

5 2. The combination with an elevated support and two pairs of drums or sheaves, of gearing for each pair of drums or sheaves, two motors each coupled up to the gearing of both pairs of drums or sheaves, and two endless chains, each mounted on two drums or sheaves.

3. The combination with an elevated support and two pairs of drums or sheaves thereon, of an independent motor for each pair of drums or sheaves, gearing connecting both pairs of drums whereby the drums or sheaves may be rotated in the same or in opposite directions, and two chains each chain passing over a drum of each pair.

20 4. The combination with an elevated support and two drums or sheaves thereon, of gearing for each drum or sheave, two motors each coupled up to the gearing of both drums or sheaves and a chain carried by said drum or sheaves.

5. The combination with an elevated support two drums thereon, and a single chain suspended from both drums, of two motors and gearing connecting both motors and the drums whereby either or both motors can independently or simultaneously transmit mo-

tion to both drums, whereby the drums may be rotated in the same or in opposite directions or be rotated at different rates of speed.

6. The combination with two shafts, of a 35 toothed wheel loose on each shaft, the two wheels intermeshing, a pinion fast to each toothed wheel, an internal and external spur-wheel loose on the hub of each toothed wheel, a disk secured to each shaft, each disk carrying pinions engaging the internal teeth of its spur-gear and the pinion fast to the toothed wheel, a drum fixed on each shaft, means for imparting motion through the toothed wheels, and a pinion meshing with the external teeth 40 of the two spur gear-wheels.

7. The combination with an elevated support, drums thereon, means for revolving the drums in the same or in opposite direction, of endless chains carried by the drums, sheaves 50 resting in the chains and carrying a cross-head, a sprocket-wheel carrying an endless chain and means for revolving said sprocket-wheel.

In testimony whereof we have signed this 55 specification in the presence of two subscribing witnesses.

WILLIAM HENRY MORGAN.
CLARENCE L. TAYLOR.
